Application December 8, 1937, Serial No. 178,629

4 Claims. (Cl. 236—26)

My invention relates to heating apparatus and more particularly to improvements in draft regulating devices for furnaces.

It is an object of my invention to provide a draft regulating device, which is relatively simple and inexpensive in construction; one which is relatively smooth in its operation and requires a relatively small operating force; one which is easy to adjust so that the furnace may be made 5 to operate in any desired manner; and one which remains in adjustment, after it has once been made.

The invention consists in the novel construction and combination of parts, to be more fully 10 described hereinafter, and the novelty of which will be particularly pointed out and distinctly claimed.

In the accompanying drawings, to be taken as 15 a part of this specification, I have fully and clearly illustrated a preferred embodiment of my invention, in which drawings:

Fig. 1 is a side elevation of a boiler furnace in which my improvement is incorporated;

Fig. 2 is a fragmentary vertical section taken 20 on the line 2—2 of Fig. 1;

Fig. 3 is a fragmentary vertical section taken 25 on the same plane as Fig. 2 and showing the draft check damper and operating means in their open position;

Fig. 4 is an enlarged fragmentary side elevation of the draft check damper and its operating means;

Fig. 5 is a fragmentary plan section on the 30 line 5—5 of Fig. 2;

Fig. 6 is a fragmentary perspective view showing the smoke pipe, the draft pouch, the draft 35 check and draft dampers, and the operating linkage for the dampers; and

Fig. 7 is a fragmentary vertical section through 40 the draft pouch and draft damper taken on the line 7—7 of Fig. 6.

Referring now in detail to the construction 45 illustrated, the reference numeral 10 indicates a boiler furnace of the coal-fired type. In so far as the present invention is concerned, the boiler furnace 10 may be either a hot water boiler or a steam boiler, depending upon the particular heating system desired by the occupants of the house in which the furnace is installed. The 50 reference character 11 indicates the usual firing door for the furnace and 12 the ash pit door.

Arranged at the rear of the furnace 10, is a 55 draft pouch 13 which is formed as a single casting and is bolted to the rear side of the base of the furnace and provides a passage through

which air for supporting combustion may flow into the furnace and beneath the usual grate (not shown). The reference character 14 indicates a flue or smoke pipe connection for the furnace, in which is located the customary stack damper 5 15 and to which is connected an offtake pipe 16 which conducts away the products of combustion to a chimney (not shown).

The upper end of the draft pouch 13 is shown as being provided with a rectangular shaped 10 draft inlet opening 20 through which the air for supporting combustion flows, and in this opening 20 is pivotally mounted a draft damper 21 which is preferably of the butterfly type and controls the flow of air through the inlet 20 and into the 15 furnace.

I provide a U-shaped frame 22 which extends along the upper defining wall and half way down the opposed defining side walls of the opening 20 and is secured to the pouch by suitable screws 20 (not shown). The inner edges of the frame 22 overhang the adjacent defining walls of the opening 20, as shown in Fig. 7. The lower ends of the two legs of the U-shaped frame 22 are provided respectively with upstanding bearing lugs 25 24 which receive pivot pins 25. The draft damper 21 is here shown as comprising a pair of rectangular plates 26 and 27 secured together at their overlapping edges by suitable bolts 28. The plate 27 is provided at its upper corners with a 30 pair of upwardly extending lugs 23 which receive respectively the pivot pins 25 carried by the bearing lugs 24.

The aligned lugs 24 and 23 and pivot pins 25 35 form the pivotal support for the draft damper 21, about which the damper may be moved from open to closed position, and vice versa. In the closed position of the draft damper 21, the lower and side edges of the plate 27 engage the outer upper surfaces of the lower half of the defining 40 walls of the opening 20 and the upper and side edges of the plate 26 engage the overhanging under surface of the frame 22. In opening, the plate 27 swings outwardly and the plate 26 inwardly, as shown in dotted lines in Fig. 6.

The draft damper 21 is so constructed that it 45 closes and remains closed by its own weight, the plate 27 being constructed heavier than the plate 26. The draft damper 21 includes an operating lug 29 which is secured at one end to the plate 27 50 and projects outwardly from one side of the damper and is provided with an opening or eye 30 at its outer end. When the lug 29 is lifted, the draft damper will move about its pivotal axis formed by the pins 25 to any desired open posi- 55

tion and thereby permit air for supporting combustion to flow into the furnace.

At the side of the smoke pipe connection 14, is provided a rectangular draft-check inlet opening 34 and within this opening is pivotally mounted a draft-check damper 35. A U-shaped frame 36 is secured to the smoke pipe connection and extends across the top and half way down the sides of the draft check inlet opening 34, and the inner sides of the frame overhang the adjacent defining walls of the opening. The lower ends of the frame 36 are provided with outwardly extending aligned bearing lugs 7 which are adapted to receive bearing pins 38 and 39, respectively. The draft-check damper 35 is also preferably of the butterfly type, as this construction permits a better balancing of the damper and thereby reduces the force required for its operation. The damper comprises a pair of plates 40 and 41 secured together along their overlapping meeting edges by suitable bolts 42. The plate 41 is provided at its upper corners with outwardly extending bearing lugs 43 which receive, respectively, the inner ends of the pins 38 and 39. The draft-check damper 35 is also constructed so that it closes and remains closed by its own weight, this being due to the fact that the plate 41 is made heavier than the plate 40 and that the plate 41 is provided with an outwardly extending counter-weight projection 44.

In the closed position of the draft-check damper, the under surfaces of the side and lower edges of the plate 41 rest upon the upper surfaces of the walls defining the lower half of the opening 34, and the upper surfaces of the side and upper edges of the plate 40 engage the overhanging under surfaces of the frame 36. In opening, the plate 41 swings outwardly and the plate 40 swings inwardly, as shown in full lines in Fig. 3 and in dotted lines in Fig. 6. This arrangement is advantageous in a draft-check damper for it aids in preventing the escape of combustion gases into the cellar or basement wherein the furnace is installed. The draft-check damper 35 also includes an operating lug 45 which is fixed at one end to the plate 41 and extends beyond the side of the damper 35 (see Fig. 4).

In furnaces of the type described, it is desirable to have a regulating device to vary the positions of the draft and draft-check dampers in response to a changing operating characteristic of the furnace. It is customary for the regulating device to operate automatically in response to a selected function of the heat output of the furnace, to close the draft damper and open the draft-check damper when the heat output increases beyond a predetermined point, and to close the draft-check damper and open the draft damper when the heat output of the furnace decreases below a predetermined point.

In accordance with the present invention, I provide a smoothly operating draft regulating device which performs effectively the above stated functions. As can be seen from an examination of Fig. 1, a regulator lever 47 is mounted on the top of the furnace 10 and is movable about a horizontal axis in response to changes in heat output of the furnace. One end of the lever 47 overlies the dampers 35 and 21 and a connecting-rod means 48 depends from such overlying end and is movable up and down therewith and is connected by lost-motion connecting means with the draft damper 21 and with the draft-check damper 35.

The regulator lever 47 comprises a rocker member 50 having a fulcrum support indicated at 51 and a regulator arm 52 extending across and carried by the upper part of the rocker member 50 and including an outer end 53 from which the connecting rod means 48 depends. The rocker member 50 is operatively connected at 54 to a thermal-responsive element 55 and the latter functions to move the rocker member 50 and arm 52 about the fulcrum 51 in response to changes in heat output of the furnace.

In so far as the present invention is concerned, the thermal-responsive element 55 may be of any suitable construction and it may operate in response to any desired characteristic which reflects changes in the heat output of the boiler furnace 10; for example, the element 55 may be actuated in response to temperature changes in a hot water boiler or changes in steam pressure in a steam boiler. In the construction shown, an increase in heat output will cause the rocker member 50 and regulator arm 52 to move in a clockwise direction about the fulcrum support 51, as viewed in Fig. 1, and thereby lower the end 53 of the regulator arm; and a decrease in heat output will result in the rocker member 50 and arm 52 being moved counterclockwise about the support 51 and in raising the end 53 of the arm 52.

The operation of the regulator arm 52 may be so adjusted that the arm can be moved in the above described manner by the thermal responsive device 55 when the water temperature or steam pressure reaches or falls below any desired value. To this end, weights 56 are detachably secured to the arm 52 at opposite sides of the fulcrum 51, and by changing the position of these weights on the arm, the degree of operating force required to move the lever may be changed at will, as is well known to those skilled in the art.

The connecting rod means 48 comprises an upper rod 60 and a lower rod 61. The upper part of the rod 60 is screw threaded, as indicated at 62, and threadedly engages a nut-device or clevis 63 pivoted to the outer end 53 of the arm 52 by a suitable pin 64 extending through aligned openings in the end 53 and clevis 63. The lower end of the rod 60 is pivotally connected by a transversely extending pivot pin 65 to the upper end 50 of the lower rod 61. Thus, the rods 60 and 61 are functionally one rod which depends from a single end of the lever 52 and which, as will presently appear, operates both the draft damper and the draft-check damper.

The lower end of the second connecting rod 61 extends through the eye or opening 30 in the operating lug 29 of the draft damper 21, and attached to the extreme lower end thereof is a collar 70 which is held at any desired adjusted position on the rod by suitable lock nuts 71 threadedly engaging the lower end of the rod 61. The opening 30 is of sufficient size to loosely receive the lower end of the rod 61. Therefore, the opening 30 and collar 70 provide a lost-motion connection between the rod 61 and the draft damper 21. As the rod 61 moves downward due to a rise in steam pressure or water temperature, the draft damper 21 is permitted to close by its own weight; and, when the latter is closed, further movement of the rod 61 results in the rod sliding in the opening 30 and in the collar 70 moving downward and away from the lug 29. Upward movement of the rod 61 will have no effect on the damper until the ball-shaped upper 75

end of the collar engages the underside of the lug 29. When the latter happens, further upward movement of the rod will result in lifting and opening the damper 21, as can be seen by the 5 dotted line position of the damper 21 in Fig. 6.

In accordance with the present invention, I have also provided a lost-motion connection between an intermediate portion of the rod means 48 and the draft-check damper 35. This connection is here shown as being provided by an intermediate lever 75 of the first class which is advantageously pivoted or fulcrumed to the outer end of the pivot pin 38 of the draft-check damper. The lever 75 comprises an arm 76 which is pivotally connected at its outer end by the transversely extending pin 65 to the adjacent ends of the rods 60 and 61. Thus, upward and downward movement of the rods 60 and 61 by the arm 52 results in the lever 75 being moved about the pivot pin 38. The lever 75 also comprises an arm 77 which, when the lever is moved in a counter-clockwise direction, as viewed in Figs. 2 and 3, is adapted to engage the inner or underside of the lug 45 and lift and open the draft-check damper 25 against its own weight. When the lever is moved in a clockwise direction, the draft-check damper is permitted to close by its own weight, and further movement of the lever in that direction will cause the arm 77 to become disengaged from the 30 lug 45 and draft-check damper 35.

From the above, it will be apparent that as the rod means 48 moves downward due to an increase in steam pressure or water temperature beyond the predetermined point determined by the 35 position of the weights 56, the draft damper 21 will be permitted to close by its own weight, and the draft-check damper 35 will be opened by the lever 75. Conversely, when the rod means 48 is moved upwardly upon a decrease in steam pressure or water temperature, the draft-check damper 35 will be permitted to close by its own weight, and the draft damper 21 will be opened by the upper end of the collar 70 engaging the lug 29 and raising the damper 21.

Preferably, my improved draft regulating device is so adjusted that the draft-check damper will just begin to open as the draft damper is closed, and also so that the draft damper will begin to open as the draft-check damper is closed. 45 However, this relationship may be changed, if desired. The time of opening and closing of each of the dampers with respect to the closing and opening respectively of the other damper may be readily varied by changing the position of the 50 collar 70 on the lower end of the rod 61, thereby changing the effective length of the rod 61. This can be done readily by changing the adjustment of the lock nuts 71 on the rod 61.

The effective length of the upper rod 60 may be 60 readily changed so as to adapt the range of movement of the rods and dampers to the range of movement of the particular regulator lever. This is effected by disconnecting the pin 65 and screwing the rod 60 upward or downward in the clevis 65 63. When the desired effective length of the rod 60 is attained, the adjacent ends of the rods 60 and 61 and the lever 75 are again readily secured together by inserting the pin 65. A suitable cotter pin 80 extending through an opening in the end of the pin 65 serves to maintain the pivot connection between the rods and lever. This last adjustment may also be used to vary the full open positions of either of the dampers, if it is found necessary.

70 75 The adjustment of the effective length of the

rod 60 cannot be varied after it is once made unless the pins 80 and 65 are removed, and the effective length of the rod 61 cannot be changed unless the lock nuts 71 are loosened.

From the above, it is apparent that I have provided an improved form of draft regulating device which is relatively simple and inexpensive in construction. As both dampers are operated from one end of the regulator arm, complexity in linkage and awkwardness in arrangement are avoided. On account of the fact that the lever 75 is connected by a pin with the rods 60 and 61, and is fulcrumed to move about the same axis as the draft-check damper, there is no sliding friction whatsoever in the movement of the lever by 10 the rods 60 and 61, and in the movement of the draft-check damper by the lever. The operation of the check damper is, therefore, effected with the greatest ease obtainable, and this is an important factor in the smooth operation of my 15 improved regulating device. There is also very little sliding friction at the draft inlet damper 21, because the ball-shaped upper face of the collar 70 rolls on the surface of the eye 30 and does not do much sliding. In the construction 20 25 closed, care has been taken to eliminate sliding friction as much as possible, because if one loose part works on another part with sliding friction between them, the resistance is relatively high; and this is the reason for a jerky operation. An 30 additional reason for smoothness in operation of my improved damper-operating mechanism is that the weight of the arm 76 of the lever 75 and the weight of the rod 61 are greater than the weight of the arm 77 and the unbalanced weight 35 of the damper 35. Hence, when the rod means 48 is moving downward and as the draft damper 21 closes and the unbalanced weight thereof is released from the rod means, the rod means 48 does not change over and become a downwardly 40 pushing element in order to open the draft-check damper 35. The pull on the rod means 48 is merely diminished when the damper 21 closes by an amount equal to the unbalanced weight of the 45 draft damper, and the opening of the draft-check is therefore effected smoothly and without the usual attendant jerks in the operation of prior draft-regulating devices.

What I claim and desire to secure by Letters 50 Patent of the United States is:

1. Control mechanism for furnaces having an inlet for air, comprising a damper pivoted to move about a fixed axis for controlling the flow of air through said inlet and weighted so as to be biased to closed position; said damper including a portion extending therefrom and adapted to be engaged at one side thereof for moving said damper in an opening direction; a lever of the first class pivoted to move about the same axis as said damper and including first and second arms; said first arm extending from the pivotal axis toward said extending portion of the damper and separably engaging said one side of said extending portion; and means including a lengthwise 55 movable rod pivotally connected throughout its movement to the outer end of said second arm and operating in response to an increase in heat output of the furnace for moving said lever in a direction to effect engagement of said first arm 60 and said one side of said extending damper portion for opening said damper, and operating in response to a decrease in heat output for moving said lever in a direction to permit closing of said 65 damper and effect separation of the engaging 70 75

- surfaces of said first arm and said extending portion of said damper.
2. In furnace apparatus of the type including a smoke outlet having a check-draft inlet opening therein; a check-draft damper pivoted to move about a fixed axis for controlling the flow of air through said inlet and weighted so as to be biased to closed position; said damper including an operating element extending therefrom and adapted to be engaged at one side thereof for moving said damper in an opening direction; a lever of the first class pivoted to move about the same axis as said damper and including first and second arms; said first arm extending from the pivotal axis toward said element and separably engaging said one side thereof; and means including a lengthwise movable rod pivotally connected throughout its movement to the outer end of said second arm and operating in response to an increase in heat output of the furnace for moving said lever in a direction to effect engagement of said first arm and said one side of said element for opening said damper, and operating in response to a decrease in heat output for moving said lever in a direction to permit closing of said damper and effect separation of the engaging surfaces of said first arm and element.
3. In furnace apparatus of the type including a smoke outlet having a check-draft inlet opening therein; a check-draft damper pivoted to move about a fixed axis for controlling the flow of air through said inlet and weighted so as to be biased to closed position; said damper including an operating lug extending therefrom and adapted to be engaged at one side thereof for moving said damper in an opening direction; a lever of the first class pivoted to move about the same axis as said damper and including first and second arms; said first arm extending from the pivotal axis toward said lug and separably engaging said one side thereof; a damper regulator comprising a second lever having an end movable towards the outer end of said second arm in response to an increase in heat output of the furnace and movable away from said second arm in response to a decrease in heat output; a rod pivotally connected at one end to the outer movable end of said second lever and pivotally connected at its other end to the outer end of said second arm; one of said pivotal connections including a nut device threadedly engaging the rod and the other of said pivotal connections including a removable pivot pin extending transversely through said rod and preventing rotation of said rod when in operative position.
4. In furnace apparatus of the type including a smoke outlet casing having a check-draft inlet opening therein; a check-draft damper pivoted to move about a fixed axis for controlling the flow of air through said inlet and weighted so as to be biased to closed position; said damper including an operating lug extending therefrom at points spaced from the pivotal axis and adapted to be engaged at one side thereof for moving said damper in an opening direction; a lever of the first class pivoted to move about the same axis as said damper and including a first arm extending toward and separably engaging said one side of said lug and including a second arm extending from the pivotal axis in such a direction that a downward force applied to the outer end thereof will effect engagement between the first arm and lug to open the damper and an upward force applied to the outer end thereof will permit closing of the damper and effect disengagement between the second arm and lug; a damper regulator comprising a second lever having an end arranged above the outer end of said second arm and movable downward in response to an increase in heat output of the furnace and upward in response to a decrease in heat output of the furnace; and a rod pivotally connected at its upper end to said outer end of said second lever and pivotally connected at its lower end to the outer end of said second arm.

BERNARD GOERG.
